 Western Electric Company, Incorporated, New
 York, N. Y., a corporation of New York

Application April 7, 1939, Serial No. 266,520

2 Claims. (Cl. 261—79)

This invention relates to spray booths, particularly the type employed in coating articles with paint or the like.

In spraying articles with coating material such as paint various problems arise certain of which are believed quite important, such as the exhausting of the air laden with the excess coating material, the cleansing of the air of such material and the elimination of particles of the excess material from becoming deposited upon the walls of the spray booth.

An object of this invention is to provide a spray booth which is simple in structure yet efficient in exhausting excess coating material.

With this and other objects in view, the invention comprises a spray booth having a coating compartment wherein there is disposed a liquid screen in front of the walls of the compartment to prevent particles of excess coating material from depositing thereon, the said particles being drawn from the compartment by a current of air which is cleansed of the particles by first drawing them through the liquid screen, then moving them helically against a spray of cleansing fluid, and finally, should any particles remain in the air current, moving them in a zigzag path between baffle plates.

Other objects and advantages will be apparent from the following detailed description when taken in conjunction with the accompanying drawing, wherein

Fig. 1 is a side elevational view of the spray booth, portions thereof being shown in section;

Fig. 2 is a top plan view of the spray booth, a portion thereof being broken away;

Fig. 3 is a fragmentary sectional view taken along the line 3—3 of Fig. 1, and

Fig. 4 is a fragmentary sectional view taken along the line 4—4 of Fig. 1.

Referring now to the drawing, particularly Figs. 1 and 2, it will be observed that the spray booth is of the type which may be mounted upon the floor, having a compartment 10, which might be termed a coating compartment, open at the front and with closed side walls 11, an inner or back wall 12 and top 13. A bottom wall 15 of this compartment terminates short of the back wall, providing a passageway 16 adjacent the lower portion of the back wall and for the full width thereof. Upon the bottom wall 15 of the coating compartment is disposed a support 18 of any suitable type, which in the present instance is a rotatable table or platform upon which articles may be disposed while being coated.

A trough or fluid receiving member 20 extending the full width of the inner or back wall 12 is secured in place, as illustrated in Figs. 1 and 4, this trough being of the cross sectional contour shown in Fig. 1 and having its lower portion positioned adjacent the back wall so that a fluid overflowing the trough will travel in the form of a curtain down the back wall and through the passageway 16. The upper edge of the trough 20 has a multiplicity of notches 21 formed therein to assist in even distribution of the fluid over the back wall as it overflows the trough. In the present instance a fluid for the trough 20 may be supplied from a pipe line 23 leading to a suitable supply (not shown). As illustrated in Fig. 4, the pipe line 23 extends through the top wall 13 and into the trough 20, where it is connected to another pipe 24 extending longitudinally through the trough with both ends thereof closed yet provided with a plurality of passageways 25 to supply the fluid to the trough uniformly throughout its length.

By viewing Fig. 1 it will be observed that a wall 28 cooperates with the wall 12 together with an extension 29 of the wall 12 in addition to the side walls of the spray booth, in forming the passageway 16. The passageway 16, therefore, provides communication between the coating compartment 10 and the cleansing portion of the spray booth, which cleansing portion includes, in addition to the fluid curtain through which air, laden with particles of coating material, is drawn, means lying in the path of travel of the air to free the air to these particles of coating material. One of these means consists of a series of spiral compartments having walls 31 spiral in formation, as illustrated in Fig. 3, positioned between the extension 29 and a partition 32 providing inlet openings 33 for the entrance of the air. Outlet openings 34 are disposed in the partition 32 in the location shown in Fig. 3, providing walls, indicated at 35, adjacent the inlet openings 33 for a purpose hereinafter described.

The partition 32 separates the lower portion of the cleansing compartment and extends downwardly into a fluid supply 38, as illustrated in Fig. 1, the partition being formed angularly to assist in directing the travel of the air from the passageway 16 to the inlet openings 33.

In the upper portion of cleansing compartment is disposed a series of baffle plates 40 positioned, as illustrated in Fig. 2, to cause a zigzag movement of the air in travelling from a passageway 42 to an outlet 43, the latter communicating with means for creating an air current through the

spray booth. This means is represented at 44 and may be any suitable exhausting fan or the like. The baffle plates 48 are positioned with their upper ends mounted in angle members 46 carried by the top of the booth. The lower ends of the baffle plates extend into a tray 48 and rest upon a perforated shelf 49. The perforations in the shelf 49 permit excess coating material, should any remain in the air by the time it reaches the baffle plates and become lodged on the plates, to pass into the tray 48. A drain 58 extends from the tray 48 into the fluid supply 38.

As shown in Figs. 1 and 2, a nozzle 53 is provided for each spiral compartment, these nozzles being positioned axially with the center lines of their respective outlet openings 34 to cause a liquid spray to pass into the spiral compartments against the direction of movement of the current of air caused by the exhaust fan 44. The nozzles 53 are connected to pipe lines 54 which extend rearwardly through the back wall of the cleansing compartment and are connected to a main supply line 55. The liquid, which in the present instance is water, is withdrawn from the supply 38 through a suction pipe 59 by a pump 60 which forces the liquid through the main supply line 55, the pipe lines 54, and through the nozzles 53. As illustrated in Figs. 1 and 2, the pipe line 23 is connected to the main supply line 55 and through the operation of the pump 60 liquid will be fed from the supply 38 to the trough 28 as well as to the nozzles 53. A float valve 62 connected in a main supply line 63 is controlled by the fluid supply 38 to maintain the fluid at a constant level, which level is above the suction pipe 59. A drain 65 adjacent the bottom of the cleansing compartment which, for the purpose of the claims, might be termed a liquid supply tank, provides means for draining the liquid from the tank and removing with it the particles of coating material which have been removed from the air. A door 66 in one wall of the cleansing compartment enables the operator to determine whether or not the nozzles are operating effectively.

To condition the spray booth for use the exhausting fan 44 and the pump 60 are set in operation, the fan creating a current of air which travels in the path indicated by the arrows in Fig. 1, while the pump 60 starts circulation of the liquid from the fluid supply 38 through the various nozzles, and also supplying a sufficient amount of the liquid to the trough 28 so that there will be a constant overflow forming a liquid curtain in front of the back wall 12 of the compartment 10.

Let it be assumed that an article to be coated is placed upon the table 18 and that coating material is sprayed thereon. The direction of travel of the coating material from a spray gun to the article would be, in general, toward the back wall 12. Therefore, excess particles of the coating material which would not be stopped by the article would continue toward the back wall 12 of the compartment. However, the current of air will intercept the major portion of these particles of excess coating material and carry them through the passageway 16. If certain of the particles should be travelling at a rate of speed greater than would be possible for them to be controlled by and included in the current of air, such particles would be sufficiently interrupted in their travel with the air current that they could be stopped by the liquid curtain and prevented from engaging the back wall 12.

Such particles would travel downwardly in the liquid curtain and pass into the supply 38. The particles of coating material remaining in the current of air pass through the passageway 16, where it is a tendency of the current of air to draw the particles through the liquid curtain. If the particles of coating material remain in the current of air after passing through the liquid curtain they are directed toward the various inlet openings 33, where the current is divided into smaller currents and caused to travel helically in the various spiral compartments. The walls 35 of each compartment prevent the smaller currents of air from escaping to the outlet openings 34 immediately upon entering the inlet openings. Therefore, these currents must travel helically for some distance before they are allowed to pass through the outlet openings. During the travel of the smaller currents of air from the inlets 33 to the outlets 34 they are opposed by their individual sprays entering the compartments from their respective nozzles 53, these sprays of liquid removing the particles of excess coating material which have remained in the air currents during the travel thus far.

The smaller air currents leaving the outlet openings 34 through the sprays of liquid merge again into a common air current which includes a smaller quantity of the liquid in vapor form. The final step is taken after the current of air passes through the passageway 42 and is caused to travel in multitudinous zigzag interrupted paths between the baffle plates 48 which remove any liquid remaining in the air. Any liquid being deposited upon the walls of the baffle plates will travel downwardly and enter the tray 48 through the apertures in the shelf 49 and from the tray a liquid will pass again into the supply 38 through the drain 58.

In the present embodiment the trough 28 is only shown adjacent the back wall 12 but it should be understood that this trough may also extend across the end walls 11, with the pipe 24 also extended to supply a liquid curtain in front of the three main walls of the coating compartment. The liquid curtain not only eliminates the possibility of the excess particles of coating material from being deposited thereon but provides the first of the three steps of removing the particles of excess coating material from the air and depositing them in the liquid supply 38. A second and important step in cleansing the air of the particles of coating material consists in the effect of the spiral compartments on the air current. These compartments divide the main air current into a plurality of smaller currents to cause the smaller currents to move helically through sprays of liquid and travel in a direction against the force of the liquid in order to continue their travel. The helical movement of the air currents through the compartments is at high velocity, the curvature of the compartments causing the air currents to travel through and against the force of the liquid sprays and as a result thereof the paint particles will be picked up by the liquid while they are forced outwardly by centrifugal force, by the travel of the air, against the walls of the compartments. The liquid, with the paint particles therein, will flow down the walls of the compartments, out the outlet opening and back into the supply 38. The final step, that is, the passing of the air current between the baffle plates, removes any liquid which may have been picked up by the air

current and causes the liquid to return to its original source.

The embodiment of the invention herein disclosed is illustrative only and may be widely modified and departed from in many ways without departing from the spirit and scope of the invention as pointed out in and limited only by the appended claims.

What is claimed is:

1. In an apparatus for treating a gas to remove impurities therefrom, a chamber having an axially horizontal and spirally cylindrical side wall with the spaced edges forming a slot in the wall and the chamber having an end wall with an aperture therein part of whose rim is tangent to an arc of the side wall at the bottom thereof, and means to cause gas to be cleaned to move into the chamber between the spaced edges of the side wall and substantially tangentially thereto so that the gas entering the chamber tangentially must move helically around the chamber to the aperture and axially out thereby, in combination with means to cause a spray of washing liquid to pass trans-

versely through the helically advancing gas substantially in the direction of the axis of the helical motion of the gas.

2. In an apparatus for treating a gas to remove impurities therefrom, a chamber having an axially horizontal and spirally cylindrical side wall with the spaced edges forming a slot in the wall and the chamber having an end wall with an aperture therein part of whose rim is tangent to an arc of the side wall at the bottom thereof, and means to cause gas to be cleaned to move into the chamber between the spaced edges of the side wall and substantially tangentially thereto so that the gas entering the chamber tangentially must move helically around the chamber to the aperture and axially out thereby, in combination with means to cause a spray of washing liquid to pass transversely through the helically advancing gas substantially in the direction of the axis of the helical motion of the gas and contrary to the advancing axial direction thereof.
